UNITED STATES PATENT OFFICE

NATHAN A. CARTER, OF MEMPHIS, TENNESSEE

DESIGN FOR A TRAILER BODY FOR A VEHICLE

Application filed December 10, 1931. Serial No. 42,024. Term of patent 14 years.

To all whom it may concern:

Be it known that I, NATHAN A. CARTER, a citizen of the United States of America, residing at Memphis, in the county of Shelby and State of Tennessee, have invented a new, original, and ornamental Design for Trailer Bodies for Vehicles, of which the following is a specification, reference being had to the accompanying drawings, forming part thereof.

Fig. 1 is a perspective view of the trailer body;

Fig. 2 is a plan view; and

Fig. 3 is a side elevation.

I claim:

The ornamental design for a trailer body for a vehicle, as shown.

In testimony whereof I have hereunto affixed my signature.

NATHAN A. CARTER.
